United States Patent Office

Des. 176,744
Patented Jan. 24, 1956

176,744

LAMP OR SIMILAR ARTICLE

John W. Webb, Cleveland, Ohio

Application October 12, 1955, Serial No. 38,342

Term of patent 14 years

(Cl. D48—20)

Figure 1 is a plan view of a lamp or similar article, showing my new design;

I claim:

The ornamental design for a lamp or similar article, substantially as shown.
